RAIL CLAMP

Norman L. Tilley, Fisher, Ark.

Application September 16, 1952, Serial No. 309,769

2 Claims. (Cl. 238—288)

1

This invention relates in general to accessories for railroad tracks, and more specifically to a rail clamp for railroad rails.

The primary object of this invention is to provide an improved rail clamp which may be utilized to simultaneously form a bearing surface for railroad rails and at the same time rigidly clamp the same to a cross-tie.

Another object of this invention is to provide an improved rail plate which is adapted to be mounted beneath railroad rails for clamping the same in an adjusted position, said rail clamp being of a relatively simple construction whereby the same may be quickly and easily installed and removed.

A further object of this invention is to provide an improved rail clamp which may be utilized for supporting and clamping railroad rails to cross-ties, said rail clamp being so constructed and designed whereby the same may be utilized for automatically spacing railroad rails to the desired spacing.

With these objects definitely in view, this invention resides in certain novel features of construction, combination and arrangement of elements and portions as will be hereinafter described in detail in the specification, particularly pointed out in the appended claims, and illustrated in the accompanying drawings which form a material part of this specification, and in which:

Figure 1 is a top plan view of a section of a railroad track and shows rails of the same clamped to and supported from cross-ties by rail plate construction which are the subject of this invention;

Figure 2 is an enlarged transverse vertical sectional view taken substantially upon the plane indicated by the section line 2—2 of Figure 1 and shows the relationship of the rail plate construction to rails and a cross-tie; and,

Figure 3 is an enlarged perspective exploded view of the rail plate construction and shows the details thereof.

Similar characters of reference designate similar or identical elements and portions throughout the specification and throughout the different views of the drawings.

Referring now to the drawings in detail, it will be seen that the rail plate construction, which is the subject of this invention, is referred to in general by the reference numeral 10. The rail plate construction 10 includes a first rail plate member 12 and a second rail plate member 14 which are adapted to coact for the pur-

pose of supporting and clamping railroad rails to a cross-tie.

It will be noted that the rail plate member 12 includes an elongated plate 16 which has secured to the upper surface thereof adjacent one end a transversely extending rail clamping element 18 which has a first flange 20 overlying a portion of the plate 16 and secured thereto by a suitable fastener 22. It will be understood that the flange 22 may be also secured to the plate 16 by any other suitable fastening means including welding. The rail clamping element 18 also includes a second flange 24 which is integral with the first flange 20 and extends inwardly and upwardly therefrom. It will be noted that the rail clamp element 18 has an end portion thereof which extends beyond an edge of the plate 16.

Also carried by the plate 16 is a second rail clamping element which is referred to in general by the reference numeral 26. The rail clamping element 26 is positioned a distance inwardly of the other end of the plate 16 and has an inwardly directed first flange 28 which overlies a portion of the plate 16 and is secured thereto by a suitable fastener 30. The rail clamping element 26 also includes an outwardly and upwardly directed second flange 32 which is in spaced relation to the plate 16. It will also be noted that the rail clamping element 26 also extends outwardly of an edge of the plate 16 from the same side as does the rail clamping element 18.

The rail plate member 14 also includes an elongated plate 34 which has secured adjacent one end thereof a rail clamping element 36. The rail clamping element 36 includes a first flange 38 which overlies an end portion of the plate 34 and is secured thereto by a suitable fastener 40. The rail clamping element 36 also includes a flange 42 which is integral with the flange 38 and extends inwardly and outwardly therefrom in spaced relation to the plate 34. The rail clamping element 36 projects beyond one edge of the plate 34 for engagement over the plate 16.

Also carried by the plate 34 and spaced inwardly of the other end thereof is a rail clamping element which is referred to in general by the reference numeral 44. The rail clamping element 44 includes a horizontal flange 46 which overlies a portion of the plate 34 and is secured thereto by a suitable fastener 48. The rail clamping member 44 also includes a flange 50 integral with the flange 46 and extending upwardly and outwardly therefrom in spaced re-

lation with respect to the plate 34. It will be noted that the rail clamping member 44 projects over a side edge of the plate 34 in the same direction as does the rail clamping member 36.

It will be noted that the flange 28 of the rail clamping member 18 is provided in the overhanging portion thereof with an aperture 52 which is in alignment with an aperture 54 in an adjacent end of the plate 34. Also, the flange 46 is provided with an aperture 56 in its projecting portion which is in alignment with an aperture 58 in an inwardly spaced portion of the plate 16.

At the other ends of the rail plate members 12 and 14, the flange 38 is provided with an aperture 60 which is in alignment with an aperture 62 in the opposite end of the plate 16. The flange 28 also has an aperture 64 in its projecting portion which is aligned with an aperture 66 in an inwardly spaced portion of the plate 34.

The plates 16 and 34 are further modified in that the plate 16 is provided with an elongated groove 68 of a size to receive an elongated tongue 70 projecting from one side of the plate 34.

Referring now to Figures 1 and 2, it will be seen that there is illustrated a railroad track construction which is referred to in general by the reference numeral 72. The railroad track construction 72 includes a plurality of cross-ties 74 on which are mounted in spaced parallel relation elongated railroad rails 76 and 78. Overlying each of the cross-ties 74 and underlying the railroad rails 76 and 78 is a rail plate construction 10 the rail plate construction 10 forming a bearing surface for the railroad rails 76 and 78 and clamping the same to the cross-ties 74 in the proper spaced relation.

It will be noted that when the rail plate constructions 10 are properly positioned on the cross-ties 74 in rail clamping relation, that each of the same has its tongue 70 received within the groove 68 and the projecting portions of the rail clamping members 18, 26, 36 and 44 overlying the plates 16 and 34. At the same time, the flanges 24, 32, 42 and 50, respectively, thereof overlie bases of the rails 74 and 76 to clamp the same. After the rail plate members 12 and 14 have been so positioned, the same are secured to their respective cross-ties 74 by driving a spike 80 or the like through the aligned apertures 52 and 54. A similar spike 82 is driven through the aligned apertures 56 and 58; a spike 84 is driven through the aligned apertures 64 and 66, and a spike 86 is driven through the aligned apertures 60 and 62.

Due to the novel construction of the rail plate members 12 and 14, it will be seen that they may be quickly positioned between the rails 76 and 78 and the cross-ties 74 and secured in place by four spikes. It will also be noted that the spikes not only position the rail plate members 12 and 14 but cause the same to tightly clamp the rails 76 and 78 in position.

Inasmuch as the rail plate members 12 and 14 are positioned with respect to each other by both the tongue and the groove connection and the aligned overlying apertures, it will be seen that the relationship of the rails 76 to the rails 78 is fixed. By manufacturing the rail plate constructions 10 for a specific type of railroad

rail, the rails 76 and 78, when clamped to the cross-ties 74 by the rail plate construction 10, will be set at the proper gauge and gauging of the track will be unnecessary. Inasmuch as railroad lines having heavy traffic travel thereover require re-gauging at regular intervals, it will be seen that the automatic gauging feature of the rail plate construction 10 will be a labor-saving feature which in addition to the labor-saving manner of installation will prove the rail plate constructions 10 to be economically feasible.

The operation of this device will be understood from the foregoing description of the details thereof, taken in connection with the above recited objects and drawings. Further description would appear to be unnecessary.

Minor modifications of the device, varying in minor details from the embodiment of the device illustrated and described here, may be resorted to without departure from the spirit and scope of this invention, as defined in the appended claims.

Having thus described the invention, what is claimed as new is:

25 1. A rail plate construction for clamping railroad rails to cross-ties, said rail plate construction including a pair of plates having opposite end portions adapted to underlie spaced rails, each plate having adjacent one end a first transverse clamp element adapted to overlie a rail base, second transverse clamp elements carried by said plates spaced inwardly from the other ends thereof, a first clamp element of one plate being co-operable with a second clamp element of the other plate to clamp a rail in an adjusted position, each of said first and second clamp elements extending beyond an edge of its plate and overlying the other plate, fastening means passable through said clamp elements and an underlying portion of a plate for securing the same to a cross-tie.

2. A rail plate construction for clamping railroad rails to cross-ties, said rail plate construction including a pair of plates having opposite end portions adapted to underlie spaced rails, each plate having adjacent one end a first transverse clamp element adapted to overlie a rail base, second transverse clamp elements carried by said plates spaced inwardly from the other ends thereof, a first clamp element of one plate being co-operable with a second clamp element of the other plate to clamp a rail in an adjusted position, each of said first and second clamp elements extending beyond an edge of its plate and overlying the other plate, said plates being interconnected against shifting in the direction of their lengths by an elongated tongue and groove joint extending a major portion of the lengths of said plates, said clamp elements having lengths equal to the combined widths of said plates.
